WINDING AND REWINDING MECHANISM FOR MUSIC SHEETS OR RECORDS.

1,107,559.

Specification of Letters Patent.

Patented Aug. 18, 1914.

Original application filed August 23, 1906, Serial No. 331,740. Divided and this application filed September 23, 1907. Serial No. 394,020.

To all whom it may concern:

Be it known that I, EUGENE T. TURNER, a citizen of the United States, residing at Rock Island, in the county of Rock Island and State of Illinois, have invented certain new and useful Improvements in Winding and Rewinding Mechanism for Music Sheets or Records, of which the following is a specification.

10 This invention relates to improvements in winding and rewinding mechanism for music sheets or records for use in pneumatic playing attachments for musical instruments of the type shown and described in my application for U. S. Letters Patent, Serial No. 331,740, filed August 23, 1906, and of which the present application is a division, and the primary object of the invention is to provide improved means for feeding or rewinding the sheet or record without reversing the operating motor.

15 A further object is to provide an improved device of this character which may be readily applied within the casing of a piano or the like, and which may be as readily removed.

20 A further object is to provide an improved device of this character which will be simple, cheap and durable in construction and efficient and effective in operation.

25 To the attainment of these ends and the accomplishment of other new and useful objects, as will appear, the invention consists in the features of novelty in the construction, combination and arrangement of the several 30 parts hereinafter more fully described and claimed and shown in the accompanying drawings illustrating an exemplification of the invention, and in which—

35 Figure 1 is a front elevation of a piano 40 with an attachment constructed in accordance with the principles of this invention applied thereto and with the front of the casing removed. Fig. 2 is a detail elevation of the record operating and winding mechanism. Fig. 3 is a sectional view on line 3—3 of Fig. 2. Fig. 4 is a sectional view on line 4—4 of Fig. 2. Fig. 5 is a sectional view on line 5—5 of Fig. 2. Fig. 6 is a sectional view on line 6—6 of Fig. 2. Fig. 7 is a detail perspective view of the locking and releasing device for the rewinding mechanism. Fig. 8 is an enlarged detail view of the lock. Fig. 9 is a detail view of one end of the rec-

ord spool or drum. Fig. 10 is a detail sectional view to illustrate the flexibility of the 55 shaft which drives the record rolls.

Referring more particularly to the drawings and in the present exemplification, the invention is shown as applied to an ordinary upright piano, the numeral 50 designating 60 generally the casing and 51 the keyboard thereof. Secured to suitable supports or brackets 87 on the piano casing is an air duct or channel 88, and spaced from and supported above this duct or channel is a second 65 air duct or channel 90, which has communication with channel 88 by means of a suitable chamber 91 located preferably adjacent one end thereof, and supported by and communicating respectively with the air ducts 70 or channels 88, 90 are a plurality of primary pneumatics 62. A main air chest or chamber 168 is supported in any desired or suitable manner, preferably in the base of the piano below the key board, and has communication with the air ducts or channels 88, 90 by means of a flexible tube or pipe 169 which leads from the chamber to a combiner chamber 170 which has communication with the air ducts or channels 88, 90, preferably 80 through the chamber 91 by means of a suitable connection 90^a. Supported by suitable brackets 98 is a record-holding frame 99, which is provided with a tracker-board 100, the latter being provided with a series of air 85 ducts or channels 101 passing therethrough. A plurality of flexible tubes or pipes 102 are secured to the tracker-board, each of which communicates with one of the air ducts or channels 101 and the other end of each is 90 respectively connected and communicates with one of the pneumatics in a manner more clearly set forth in the application above referred to.

The ordinary perforated record or music 95 sheet 103 is held upon a spool 104, passes over the tracker-board 100, and is wound upon a receiving spool 105. The spool or drum 105 is rotatably secured by one end in a suitable bearing in one side of the frame 100 99, and by a suitable bearing supported by an upright or partition 99^a adjacent and spaced from the other side of the frame, as shown more clearly in Fig. 2 of the drawings. The roller or spool 104 is provided 105 with a circumferential groove or depression

106, preferably adjacent one end thereof, as shown more clearly in Fig. 9 of the drawings, for a purpose to be set forth. This spool is journaled by one end in a suitable bearing in one side of the frame, and the other end of the roller is provided with a trunnion 107 having laterally projecting lugs 108 adapted to enter and be held in a slotted or recessed rotatable sleeve or bearing 109, mounted in the partition 99^a, shown more clearly in Fig. 2 of the drawings. Secured to this rotatable sleeve or bearing 109, preferably on the outside of the partition 99^a, is a disk 110, provided with a laterally projecting lug or pin 111, one face of which is preferably inclined for a purpose to be set forth. Secured to or carried by the end of the drum 105, preferably the end adjacent the same side of the frame to which the sleeve 109 is mounted, is a gear 112.

The partition 99^a is spaced some distance from the adjacent end of the frame 99, and secured across the front and rear edges thereof are upright plates 112^a which are adjacent and located opposite each other, as shown more clearly in Fig. 3 of the drawings. Each of these plates is provided with a diagonally disposed slot 113, which slots lie in the same plane with each other and preferably inclined downwardly toward the partition or upright 99^a. A bodily movable member or support 114 is located between the plates 112^a, and extending from the front and rear edge thereof are projections 115, as shown more clearly in Fig. 6 of the drawings, which may be secured thereto in any desired manner, but are preferably formed by the extremities of a bar or rod which extends through the member 114. The projecting extremities stand and are movable in the slots 113, so that when the member 114 is depressed, the slots will cause the member to move toward the partition 99^a, and when raised will move away from the partition and toward the adjacent ends of the frame 99.

The lower extremity of the member 114 is preferably reduced, as at 116, and passes through an aperture or opening 117, as shown more clearly in Figs. 6 and 7 of the drawings, and serves to guide the lower end and hold the same against displacement. This opening 117 is of sufficient size to permit the upper end of the member 114 to rock toward the partition 99^a when depressed. Journaled in the upper portion of this member, preferably adjacent the projections 115, and in a suitable bearing 118, is a stub shaft 119 which is held from displacement in any desired or suitable manner. This shaft is preferably located in line with the trunnion 107 of the record spool, and supported on one end thereof and rotatable therewith is a disk 120 which is preferably located adjacent to and is of substantially the same size

as the disk 110. Projecting from the face of this disk 120 is a lateral lug or extension 121, which is provided with a beveled or inclined face (shown more clearly in Fig. 2 of the drawings). These two disks 110 and 120 are adapted to be brought into close proximity to each other when the member 114 is depressed so that the lugs or projections 111, 121 will engage and interlock to form a clutch for locking the stub shaft 119 and the end of the record spool together. Supported by and rotatable with the stub shaft 119 is a sprocket wheel 122 (shown more clearly in Fig. 3 of the drawings), and a laterally projecting lug or extension 123 is arranged on the stub shaft 119, preferably at a point between the sprocket 122 and the member 114, the member 114 being normally held in its extreme upper position with the projections 115 at the tops of the slots 113 and with the disks 110, 120 separated, preferably by means of a spring 124, one end of which is secured to the member 114 and the other to the end of the frame 99.

The lower extremity of the member 114 is provided with a projecting portion 125, formed in any suitable manner and shown more clearly in Figs. 6 and 8 of the drawings. A latch or dog 126 is pivotally supported adjacent the lower end of the member 114 by means of a rod or bar 127 passing transversely therethrough, and with its ends journaled in the partition 99^a and the end of the frame 99. This latch or dog is provided with a shoulder 128, preferably formed by securing a plate to the face thereof, which is provided with an ear or extension 129 (shown more clearly in Fig. 7 of the drawings.) A spring 130 engages or rests against the latch or dog 126 and tends to force the shoulder 128 inwardly, so that when the member 114 is depressed, the projection 125 thereon will pass under and be held by the shoulder 128 to lock the member down and hold the disks 110, 120 in contact.

Passing through suitable slots 131, 132 respectively in the end of the frame 99 and the partition 99^a is one end of a flexible shaft 133, (shown more clearly in Fig. 2 of the drawings), the other end of which is journaled in a suitable support 134^a secured to the piano frame 50, as shown more clearly in Fig. 1 of the drawings, and it is to be understood that the word "flexible" is used in this connection in its broadest sense. On the extremity of the end which passes through the slots 131, 132, is a pinion wheel 134 (see Fig. 2), which meshes with the gear 112 to rotate the record receiving spool or drum 105. This shaft 133 passes through and has a bearing in the movable member 114, as shown more clearly in Figs. 6 and 7 of the drawings. Secured to and rotatable with the shaft 133 and located preferably adjacent the member 114 and the partition 99^a and in

direct line with the sprocket 122 is a sprocket 135, and passing around these sprockets is a chain or belt 136 (see Fig. 3).

Journalized preferably at the base of the 5 partition 99^a and the end of the frame is a rock shaft 137 (see Figs. 2 and 6), one end of which projects beyond the partition and terminates adjacent to and is parallel with the record receiving spool or drum 105, and 10 secured to this shaft is an arm 138 which is adapted to engage and rest upon the spool or drum 105. A suitable spring 137^a is provided to normally tend to hold the arm 138 against the spool or drum. Secured also to 15 the shaft 137 is an arm 139 (see Figs. 6 and 7) which is located adjacent the projection 129 on the latch or dog 126 and is adapted to engage the projection when the shaft 137 is rocked in a manner to be set forth, to trip 20 the latch or dog 126 to release the member 114.

Pivotedly supported by the partition 99^a adjacent the top thereof is an arm 139^a, the free end of which rests upon the record when 25 wound upon the spool or drum 104 at a point directly above the grooved or recessed portion 106 in the spool or drum 104 when the latter is in position and empty. A rock shaft 140 is journalized in the frame 30 99 and partition 99^a, with one end adjacent the arm 139^a, and secured to this shaft is an arm 141, the free end of which engages and rests upon an arm 139 as shown more clearly in Fig. 5 of the drawings.

35 Secured to the shaft 140 is an arm 142, the free extremity of which is adapted to be brought into a position in the path of movement of the lug or projection 123 on the stub shaft 119 when the latter is rotated 40 and the arm 139^a drops into the groove or recess 106 in a manner to be described. When the spool 104 contains any portion of the record, the extremity of the arm 142 will be held out of the path of movement of the 45 lug or projection 123. A suitable spring 143, one end of which is secured to the shaft 140 and the other to any suitable point, preferably one of the plates 112^a, normally tends to rock the shaft 140 to cause the extremity 50 of the arm 142 to normally tend to move into the path of movement of the lug or projection 123. If desired, the upper portion or top of the frame 99 may be held in position in any desired or suitable manner, 55 preferably by means of bars or braces 144 (see Fig. 1.)

A suitable motor is provided to rotate the shaft 146, the specific construction and operation of which motor, however, forms the 60 subject matter of a separate application. Secured to the shaft 146 is a gear 148 which is adapted to transmit motion to a suitable gear 149 on the shaft 133 when the motor is operated. This motor is provided with a 65 suction chest 151 from which the air is

adapted to be exhausted to operate the shaft 146 in the manner set forth in the application before referred to. A chamber 164 is suitably supported adjacent and communicates with the chest 151, and leading from 70 this chamber and communicating with the chamber 199 is a flexible tube or pipe 206.

A double bellows or pneumatic 171 is supported in any suitable manner and has communication with the chest or chamber 168 75 through the connection 172. A yoke 173 is connected by its ends to each side of the bellows or pneumatic 171 and also to the pulleys 174 by means of a link 175. A suitable motor 176 is geared to the pulley 174, 80 preferably by means of belts 177, 178, and the intermediate pulley 179.

When the motor is started, it operates the bellows or pneumatic 171 to suck the air from the chest or chamber 168, which in 85 turn draws the air through the ducts or channels 101 in the tracker-board 100, flexible members 102, primary pneumatics 62, air duct or channel 88, 90, chamber 170 and tubular member 169 to operate the respective pneumatics in a manner set forth in the original application above referred to. A suitable balancing bellows or pneumatic 180 90 may be provided which has communication with the chest or chamber 168 and is collapsed by the suction through the chamber in a manner set forth in the application just referred to, a suitable spring 181 being provided to return the bellows 180 to its normal 95 position. A bellows 200, which is controlled by a spring 201, has communication with the chamber 199 through the medium of the pipes 202 and chamber 203, and this bellows or pneumatic also has communication with a double bellows or pneumatic 196 through 100 the medium of a chamber 204 and the tubes or pipes 205, and the bellows or pneumatic 196 is operated by the double bellows or pneumatic 171 through the medium of a yoke 191.

Supported in any suitable manner, preferably by means of the air duct or channel 90, is a magnet 219, and in front thereof is pivotally supported an arm 221, which is adapted to be attracted by the magnet when 115 the latter is energized. An arm or lever 223 is pivoted to a suitable support 224, and the free end of the arm or lever is adapted to be forced and held between suitable contacts 225 by means of a spring 226. Projecting 120 from the side of the arm or lever 223 is a pin or projection 227 which is adapted to be engaged by a suitable shoulder on the armature 221 to lock the arm 223 out of engagement with the contacts 225 and against 125 the tension of the spring 226 to stop the motor in the manner set forth in the original application above referred to. A suitable pneumatic 228 is also supported by the air duct or channel 90, and projecting from 130

the movable member thereof is an arm or extension 230 which is adapted to engage the extremity of the arm or lever 223 to rock the latter about its point of pivotal support out of engagement with the contacts 225 and into a position to be engaged and supported by the shoulder on the arm 221 when the pneumatic 228 is collapsed.

A tube or pipe 231 leads from the bellows 10 or pneumatic 228 and communicates with the air duct or channel 90, and a similar pipe or tube 232 leads from the pneumatic or bellows 228 and connects with a port or passage in a valve casing 234. The specific construction of the casing 234 and the operation of the valve therein forms no part of the present application, but forms the subject matter of a separate application.

The valve in the casing 234 is adapted to be operated to permit the bellows or pneumatic 228 to be collapsed by means of an arm 240 which is secured to a rock shaft 239, which latter in turn is secured or connected to the valve in the casing 234. The extremity of this arm normally rests upon the sheet or record 103 when the latter is in position, and passing across the tracker-board 100, and is adapted to be engaged by a projection 241 on the record whereby the shaft 239 will be rocked and the valve operated to permit the pneumatic 228 to be collapsed in the manner set forth in the application above referred to. Suitable batteries 242 may be employed to energize the magnet 219 through the conductors 243, 244. The batteries 242 and contacts 225 may be connected to the motor 176 in the usual manner not necessary to illustrate, which forms no part of the present application, so that when the arm or lever 223 engages the contacts 225 the circuit will be completed through the conductors 247, 248 to the motor to set the latter in motion, and when the arm or lever 223 is moved out of engagement with the contacts 225, the current will be broken to stop the motor in the ordinary and well known manner. Any suitable mechanism may be employed to close the circuit to energize the magnet 219 to release the arm 223 to compel the current to start the motor, and for this purpose there is shown a coin or check controlled mechanism designated generally by the reference numeral 250, shown in Fig. 1 of the drawings.

In order to prevent the record 103 feeding too quickly from or on to the spool 104, a suitable brake 257 may be provided (shown more clearly in Fig. 4 of the drawings) which preferably engages and exerts its pressure upon the stub shaft 109.

It is thought from the above that the operation will be clearly understood, but briefly stated, it is as follows: Assuming the record to be on the spool or drum 104 and in position, with one end extending across the

tracker-board, and secured to the spool or drum 105 in the ordinary manner, and with the pinion wheel 134 on the end of the flexible shaft 133 in mesh with the gear 112 on the spool or drum 105, the primary pneumatics and the pneumatics 228, 186, being full of air, expanded, and the arm or lever 223 raised out of engagement with the contacts 225 and in such a position that the lug or projection 227 will engage and rest upon the shoulder of the armature 221, the parts will be in position to start the mechanism. When in this position, the projection 191 on the member 114 will rest against the end of and close the tubular member 190 leading to the pneumatic 186 which controls the air chamber 168, and the arms 138, 240 will engage and rest upon the record while the extremity of the arm 141 will engage and be supported by the arm 139^a. In this position, when the current is completed to energize the magnet 219, the latter will attract the armature 221, causing the shoulder to move from under the projection 227 on the arm or lever 223. The arm or lever 223 being thus released, the motor will start and a suction will be created in the air chest or chamber 168 to operate the primary pneumatics 62 as the record passes across the tracker-board. This operation will continue until the record has reached the end of the piece, at which time the projection 241 thereon will rock the arm or lever 240 to operate the valve in the casing 234 to permit the bellows or pneumatic 228 to be collapsed, which latter will raise the arm or lever 223 out of engagement with the contacts 225 to stop the motor. While any portion of the record 103 is on the spool 104, the arms 139^a will rest thereon and the arm 141 which engages the arm 139^a will hold the rock shaft 140 in such a position that the extremity of the arm or projection 142 will be out of the path of movement of the lug or projection 123. The arm or projection 138 rests against the spool or drum 105 so as to hold the arm 139 out of engagement with the projection 129 on the latch or dog 126. As the record is fed off of the spool or drum 104, the arm 139^a will move toward the periphery of the drum or roller by means of the strain exerted thereon by the spring 143, and will continue so to move until the end of the piece has been reached. At this time the end of the arm or projection 142 will have moved into the path of movement of the lug or projection 123. The disk 110 will rotate with the spool or roller 104 while the disk 120 is rotated in the opposite direction by means of the sprockets 122, 135, and the chain 136. When the record has been entirely fed off of the spool or roller 104, the end of the arm 139^a will drop into the circumferential groove or depression 106 and will permit the arm 141, under the influence 133

of the spring 143, to assume a position to permit the arm or projection 142 to move into the path of movement of the lug 123. When the lug 123 strikes said end, a further 5 rotation of the disk 120 through the medium of the sprocket chain 136 will cause the projection or lug 123 to abut against the end of the arm or projection 142, and such a movement will depress the member 114 10 against the tension of the spring 124, and as the member is depressed, the inclined slots 113 and projections 115 will cause the member 114 to move toward the partition 99^a to bring the disks 110, 120 in contact so that 15 when rotated, the projecting lugs 111, 121 will engage to lock the disks. When the member 114 is depressed, the end of the flexible shaft 133 which passes therethrough will also be depressed to disengage the pinion 134 20 and the gear 112. In this position the shoulder 128 on the dog or lever 126 will engage the shoulder 125 on the member 114, and the latter will be locked in this depressed position. A further rotation of the shaft 133 25 in the same direction will then rotate the roller 104 to rewind the record on the roller 104, the arm 142 being first grasped by the operator and raised out of the path of movement of the lug or projection 123. If desired, a suitable latch 259 may be provided 30 for maintaining the arm 139^a in its raised position.

As the record passes off the roller or drum 105, and the diameter decreases, the spring 35 137^a tends to cause the arm 138 to move toward the spool, and just as the arm engages the spool, the arm 139 will engage the projections 129 to trip the dog or latch 126 against the tension of the spring 130 to permit the spring 124 to return the member 114 40 to its normal position to disengage the disks 110, 120 and to cause the pinion 134 to engage the gear 112. The arm 139^a may then be released after a new record has been 45 placed in position. The depression of the member 114 opens or uncovers the tubular member 190, which permits the pneumatic 186 to be collapsed in the manner set forth in the above referred to original application 50 to unseat the valve 183 to permit air to enter the chest or chamber 168 for the purpose also set forth in the application just referred to.

A single record may contain a plurality 55 of pieces, and in this event and when desired to stop the motor at the end of each piece, a suitable projection 241 is secured to the record at the end of each piece.

Having thus fully described my invention, 60 what I claim as new and desire to secure by Letters Patent is:—

1. In a device of the class described, the combination of a tracker-board having a series of air passages therethrough, a plurality of individual primary pneumatics,

connections between the air passages in the tracker-board and the respective primary pneumatics, an exhaust mechanism for operating the primary pneumatics, a record strip adapted to pass over the air passages 70 in the tracker-board for controlling the primary pneumatics, means for feeding the record, a motor for operating the feeding means and the exhaust mechanism, means operatively related to the record for controlling the motor, means for rewinding the record, means for shifting the rewinding mechanism into operation, and means operatively related to the last said means and controlled by the record for preventing the 75 operation of said shifting means while the record is being fed.

2. In a device of the class described, the combination of a tracker-board having a series of air passages therethrough, a plurality of individual primary pneumatics, connections between the air passages in the tracker-board and the respective primary pneumatics, an exhaust mechanism, for operating the primary pneumatics, a record strip adapted to pass over the air passages 80 in the tracker-board for controlling the primary pneumatics, means for feeding the record, a motor for operating the feeding means and the exhaust mechanism, means operatively related to the record for controlling the motor, means for rewinding the record, means for throwing the feeding mechanism out of operation and the rewinding mechanism into operation and means operatively 85 related to the last said means and controlled by the record for preventing the 90 operation of the last said means during the feeding of the record.

3. In a device of the class described, the combination of a tracker board having a series of air passages therethrough, a plurality of individual primary pneumatics, connections between the air passages in the tracker board and the respective primary 100 pneumatics, an exhaust mechanism for operating the primary pneumatics, a record strip adapted to pass over the air passages in the trackerboard for controlling the primary pneumatics, means for feeding the record, a motor for operating the feeding means and the exhaust mechanism, means controlled by the record and adapted to be set for controlling the motor, means for rewinding the record, means adapted to be tripped 105 by the record for throwing the feeding mechanism out of operation and the rewinding mechanism into operation and without interrupting the motor, and means for locking said mechanisms in their adjusted positions.

4. In a device of the class described, the combination of a tracker-board having a series of air passages therethrough, a plurality of individual primary pneumatics, 110

connections between the air passages and the respective primary pneumatics, an exhaust mechanism for operating the primary pneumatics, a record strip adapted to pass over 5 the openings in the tracker-board for controlling the pneumatics, a motor, a flexible shaft driven by the motor for feeding the record, means operatively related to the shaft for rewinding the record, positive 10 means tending normally to bend the shaft to throw the feeding mechanism out of operation and for throwing the rewinding mechanism into operation, means operatively related to the said bending means 15 and controlled directly by the record for controlling the former, and a motor for operating the first said motor and the exhaust mechanism.

5. In a device of the class described, the 20 combination of a tracker-board having a series of air passages therethrough, a plurality of individual primary pneumatics, connections between the air passages and the respective primary pneumatics, an exhaust mechanism for operating the primary pneumatics, a record strip adapted to pass over 25 the openings in the tracker-board for controlling the pneumatics, a motor, a flexible shaft driven by the motor for feeding the record, means operatively related to the shaft for rewinding the record, positive 30 means tending normally to bend the shaft to throw the feeding mechanism out of operation and for throwing the rewinding mechanism into operation, means controlled 35 directly by the record for controlling the said bending means, a motor for operating the first said motor and the exhaust mechanism, and means operatively related to the 40 record for controlling the last said motor.

6. In a device of the class described, the combination of a tracker-board having a series of air passages therethrough, a plurality of individual primary pneumatics, 45 connections between the air passages and the respective primary pneumatics, an exhaust mechanism for operating the primary pneumatics, a record strip adapted to pass over the openings in the tracker-board for 50 controlling the pneumatics, a motor comprising a plurality of pneumatics, a flexible shaft, driven by the motor for feeding the record, means operatively related to the shaft for rewinding the record, positive 55 means tending normally to bind the shaft to throw the feeding mechanism out of operation and for throwing the rewinding mechanism into operation, means controlled by the record for controlling the said binding 60 means, a connection between the pneumatics of the motor and the exhaust mechanism for operating the last said pneumatics, and means for controlling the said pneumatics.

7. In a device of the class described, the 65 combination of a tracker-board having a series of air passages, a plurality of primary pneumatics, connections between the air passages and the respective primary pneumatics, an exhaust mechanism for the pneumatics, a record supporting roll, the record being adapted to be fed across the air passages in the tracker-board for controlling the primary pneumatics, means for feeding the record embodying a flexible shaft, means 70 operatively related to the feeding means for rewinding the record, means tending normally to automatically throw the feeding means out of operation and the rewinding means into operation when the end of the 75 record is reached and means controlled by the record for controlling the last said means.

8. In a device of the class described, the combination of a tracker-board having a 80 series of air passages, a plurality of primary pneumatics, connections between the air passages and the respective primary pneumatics, an exhaust mechanism for the pneumatics, a record supporting roll, the record 85 being adapted to be fed across the air passages in the tracker-board for controlling the primary pneumatics, means for feeding the record embodying a flexible shaft, means operatively related to the feeding means for 90 rewinding the record, means tending normally to automatically throw the feeding means out of operation and the rewinding means into operation, means controlled by the record for holding the said throwing 95 means against actuation until the end of the record is reached, and means controlled by the shifting of said record operating means to prevent the action of the exhaust 100 mechanism upon the primary pneumatics. 105

9. In a device of the class described, the combination of a tracker board, a record supporting spool on one side of the board, a record receiving spool on the opposite side of the board, means for feeding the 110 record to the receiving spool, means for rewinding the record, positive means operatively related to the spool and controlled directly by the record for shifting one of said means into and the other out of operative position, and means common to both 115 of said record operating means for actuating the latter.

10. In a device of the class described, the combination of a tracker-board, a record holding spool and a receiving spool respectively on opposite sides of the board, means for rotating either of said spools to respectively advance or rewind the record, said record spool being provided with a circumferential groove, means for throwing one of the operating means into and the other out of operation, and means adapted 120 125

to enter the groove in the spool, to permit the last said means to assume an operative position.

11. In a device of the class described, the combination of a tracker-board, a record holding spool and a receiving spool respectively on opposite sides of the board, means for rotating either of said spools to respectively advance or rewind the record, said record spool being provided with a circumferential groove normally covered by the record, means for throwing one of the operating means into and the other out of operation, and means adapted to rest upon the record for normally holding the throwing means out of operative position, said means being adapted to enter the groove in the spool when the latter is uncovered to permit the throwing means to assume an operative position.

12. In a device of the class described, the combination of a tracker-board, a record holding spool and a receiving spool respectively on opposite sides of the board, means for rotating either of said spools to respectively advance or rewind the record, said record spool being provided with a circumferential groove normally covered by the record, means for throwing one of the operating means into and the other out of operation, means adapted to rest upon the record for normally holding the throwing means out of operative position, and means for forcing the last said means into the groove in the spool when the latter is uncovered to permit the throwing means to assume an operative position.

13. In a device of the class described, the combination of a tracker-board, a record holding spool and a record receiving spool, located respectively on opposite sides of the tracker-board, means for advancing the record across the tracker-board, means for rewinding the record, means controlled by the record for shifting the advancing means out of operation and the rewinding means into operation, means for locking said means in their adjusted position, means for releasing said locking means, and means whereby the releasing means will be held out of operative position when any of the record is on the receiving spool.

14. In a device of the class described, the combination of a tracker-board, a record holding and a record receiving spool located respectively on opposite sides of the tracker-board, a movable supporting member, a clutch mechanism, one member of the clutch being operatively connected with the record holding spool, the other member being journaled in the supporting member, a flexible shaft, means for rotating the shaft, one end of the shaft being journaled in the supporting member, an operative connec-

tion between the shaft and the receiving 65 spool for feeding the record, an operative connection between the shaft and one of the clutch members, and means for moving the supporting member to throw the feeding mechanism out of operation and to cause 70 the clutch members to engage to rewind the record.

15. In a device of the class described, the combination of a tracker-board, a record holding and a record receiving spool located 75 respectively on opposite sides of the tracker-board, a movable supporting member, a clutch mechanism, one member of the clutch being operatively connected with the record holding spool, the other member being journaled in the supporting member, a flexible shaft, means for rotating the shaft, one end 80 of the shaft being journaled in the supporting member, an operative connection between the shaft and the receiving spool for 85 feeding the record, an operative connection between the shaft and one of the clutch members, and means controlled by the record for moving the supporting member to throw the feeding mechanism out of operation 90 and to cause the clutch members to engage to rewind the record.

16. In a device of the class described, the combination of a tracker-board, a record holding and a record receiving spool located 95 respectively on opposite sides of the tracker-board, a movable supporting member, a clutch mechanism, one member of the clutch being operatively connected with the record holding spool, the other member 100 being journaled in the supporting member, a flexible shaft, means for rotating the shaft, one end of the shaft being journaled in the supporting member, an operative connection between the shaft and the receiving spool 105 for feeding the record, an operative connection between the shaft and one of the clutch members, means for moving the supporting member to throw the feeding mechanism out of operation and to cause the clutch members 110 to engage to rewind the record, means for locking said supporting member in its adjusted position and means for releasing said member.

17. In a device of the class described, 115 the combination of a tracker-board, a record holding and a record receiving spool located respectively on opposite sides of the tracker-board, a movable supporting member, a clutch mechanism, 120 one member of the clutch being operatively connected with the record holding spool, the other member being journaled in the supporting member, a flexible shaft, means for rotating the shaft, one end of the shaft being journaled in the supporting member, an operative connection between the shaft and the receiving spool for feeding the record,

an operative connection between the shaft and one of the clutch members, means for moving the supporting member to throw the feeding mechanism out of operation and to cause the clutch members to engage to rewind the record, means for locking said supporting member in its adjusted position, and means controlled by the record for releasing said member.

10 18. In a device of the class described, the combination of a tracker-board, a record holding and a record receiving spool located respectively on opposite sides of the tracker-board, a movable supporting member, a clutch mechanism, one member of the clutch being operatively connected with the record holding spool, the other member being journaled in the supporting member, a flexible shaft, means for rotating the shaft, one end 15 of the shaft being journaled in the supporting member, an operative connection between the shaft and the receiving spool for feeding the record, an operative connection between the shaft and one of the clutch 20 members, means for moving the supporting member to throw the feeding mechanism out of operation and to cause the clutch members to engage to rewind the record, a latch for locking said supporting member in its 25 adjusted position, and means controlled by the record adapted to engage and trip the latch.

19. In a device of the class described, the combination of a tracker-board, a record holding and a record receiving spool located 30 respectively on opposite sides of the tracker-board, a movable supporting member, a clutch mechanism, one member of the clutch being operatively connected with the record holding spool, the other member being journaled in the supporting member, a flexible shaft, means for rotating the shaft, one end 35 of the shaft being journaled in the supporting member, an operative connection between the shaft and the receiving spool for feeding the record, an operative connection 40 between the shaft and one of the clutch members, means for moving the supporting member to throw the feeding mechanism out of operation and to cause the clutch members to engage to rewind the record, a latch for locking said supporting member in its 45 adjusted position, and means controlled by the record adapted to engage and trip the latch, and means for automatically returning the 50 supporting member to its normal position.

20. In a device of the class described, the combination of a tracker-board, a record holding and a record receiving spool, located 55 respectively on opposite sides of the tracker-board, a movable supporting member, a flexible shaft having a bearing in the member, an operative connection between the shaft and the receiving spool for feeding the record, means controlled by the supporting 60 member for rewinding the record, and op-

eratively related to the shaft, means controlled by the record for moving the member to bend the shaft to throw the feeding mechanism out of operative position, and the rewinding mechanism into operative position, a latch for locking said member in its adjusted position, a rock-shaft, an arm on the shaft adjacent the latch, means for rocking the shaft, means whereby the record will hold the rocking means out of operation and 70 permit the shaft to rock to cause the arm to release the latch, and means for rotating the first said shaft.

21. In a device of the class described, the combination of a tracker-board, a record holding and a record receiving spool located 75 respectively on opposite sides of the tracker-board, a movable supporting member, a flexible shaft having a bearing in the member, an operative connection between the 80 shaft and the receiving spool for feeding the record, means controlled by the supporting member for rewinding the record, and operatively related to the shaft, means controlled by the record for moving the 85 member to bend the shaft to throw the feeding mechanism out of operative position and to throw the rewinding mechanism into operative position, a latch for locking said member in its adjusted position, a rock shaft, 90 an arm on the shaft adjacent the latch, means for rocking the shaft, to cause the arm to engage and release the latch, means on the shaft adapted to prevent the arm from releasing the latch when the record is 95 on the receiving spool, and means for rotating the first said shaft.

22. In a device of the class described, the combination of a tracker-board, a record supporting and a record receiving spool, 100 means for feeding the record across the tracker board, means for rewinding the record, comprising two normally separated clutch members, one of said members being operatively connected to the supporting 105 spool, means for rotatively supporting the other clutch member, means for rotating said clutch member, and means adapted to be engaged by the rotating clutch member to move the supporting means to cause the 110 clutch members to engage and to throw the feeding means out of operation.

23. In a device of the class described, the combination of a tracker-board, a record supporting and a record receiving spool, 110 means for feeding the record across the tracker-board, means for rewinding the record, comprising two normally separated clutch members, one of said members being operatively connected to the supporting 115 spool, means for rotatively supporting the other clutch member, means for rotating said clutch member, and means controlled by the record adapted to be engaged by the rotating clutch member to move the sup- 120 125 130

porting means to cause the clutch members to engage and to throw the feeding means out of operation.

24. In a device of the class described, the combination of a tracker-board, a record supporting and a record receiving spool, means for rewinding the record comprising two clutch members, yielding means for holding said members normally separated, one of said members being operatively connected to the supporting spool, means for rotatably supporting the other clutch member, means for rotating said clutch member, and means controlled by the record adapted to be engaged by the rotating clutch member to move the clutch member against the tension of said yielding means to cause the clutch member to engage and to throw the feeding means out of operation.

25. In a device of the class described, the combination of a tracker-board, a record holding and a record supporting spool located respectively on opposite sides of the tracker-board, means for feeding the record across the board, means for rewinding the record comprising two normally separated clutch members, one of said members being operatively connected to the record spool, means for rotatably supporting the other clutch member, a support, a projection on said support, means operatively related to the rotating clutch member adapted to engage the projection on the support, when the latter is brought into the path of movement thereof to move the clutch members into engagement and the feeding mechanism out of operation, and means controlled by the record for causing the projection to assume a position within the path of movement of the coöperating means on the clutch member.

26. In a device of the class described, the combination of a tracker-board, a record holding and a record supporting spool located respectively on opposite sides of the tracker-board, means for feeding the record across the board, means for rewinding the record comprising two normally separated clutch members, one of said members being operatively connected to the record spool, means for rotatably supporting the other clutch member, a rock shaft, an arm on said shaft, means operatively related to the rotating clutch member adapted to be engaged by the arm on the shaft, when the latter is brought into the path of movement thereof, to move the clutch members into engagement and the feeding mechanism out of operation, and means controlled by the record for rocking the shaft to move the arm into a position within the path of movement of the coöperating means on the clutch member.

27. In a device of the class described, the combination of a tracker-board, a record

holding and a record supporting spool located respectively on opposite sides of the tracker-board, means for feeding the record across the board, means for rewinding the record comprising two normally separated clutch members, one of said members being operatively connected to the spool, means for rotatably supporting the other member, a projection on the last said clutch member, a rock shaft, an arm on the shaft adjacent the projection, means for holding the end of the arm out of the path of the movement of the projection on the clutch, and means for moving the end of the arm into a position to be engaged by the projection to cause the clutch members to inter-engage and to throw the feeding mechanism out of operation.

28. In a device of the class described, the combination of a tracker-board, a record holding and a record supporting spool located respectively on opposite sides of the tracker-board, means for feeding the record across the board, means for rewinding the record, comprising two normally separated clutch members, one of said members being operatively connected to the spool, means for rotatably supporting the other member, a projection on the last said clutch member, a rock shaft, an arm on the shaft, adjacent the projection, means for moving the end of the arm into a position to be engaged by the projection to cause the clutch members to inter-engage and to throw the feeding mechanism out of operation, and means controlled by the record for holding the end of the arm out of operative position and for permitting the arm to be moved into its operative position.

29. In a device of the class described, the combination of a tracker-board, a record holding and a record receiving spool, one of said spools being provided with a circumferential groove adapted to be covered by the record, means for feeding the record across the board, means for rewinding the record, comprising two normally separated members, one of said members being operatively connected to the spool, means for rotatably supporting the other member, a projection on the rotating member, a rock shaft, a projection on the shaft adapted to be moved into the path of movement of the projection on the rotating member, to be engaged thereby for moving the clutch members into contact and for releasing the feeding mechanism, and means on the shaft adapted to rest upon the record over the groove in the out of the said path of movement, said means being adapted to enter the groove when uncovered by the record to permit the projection on the shaft to be engaged by the projection on the clutch member.

30. In a device of the class described, the combination of a tracker-board, a record

- holding and a record receiving spool, one of said spools being provided with a circumferential groove adapted to be covered by the record, means for feeding the record
- 5 across the board, means for rewinding the record, comprising two normally separated members, one of said members being operatively connected to the spool, means for rotatably supporting the other member, a
- 10 projection on the rotating member, a rock shaft, a projection on the shaft adapted to be moved into the path of movement of the projection on the rotating member, to be engaged thereby for moving the clutch members
- 15 into contact and for releasing the feeding mechanism, means on the shaft adapted to rest upon the record over the groove in the spool, to hold the projection on the shaft out of the said path of movement, and means
- 20 for causing the last said means to enter the groove when uncovered by the record to permit the projection on the shaft to be engaged by the projection on the clutch member.
- 25 31. In a device of the class described, the combination of a tracker-board, a record holding and a record receiving spool located respectively on the opposite sides of the tracker-board, means for feeding the record
- 30 across the board, means for rewinding the record comprising two normally separated members, one of said members being operatively connected to the spool, means for rotatably supporting the other member, means
- 35 adapted to be engaged by the rotary member, whereby the further rotation of the member after it has engaged the last said means will cause the member to be moved into engagement with its coöperating member, and
- 40 means for throwing the feeding mechanism out of operation when the said member is shifted.
32. In a device of the class described, the combination of a tracker-board, a record holding and a record receiving spool located
- 45 respectively on the opposite sides of the tracker-board, means for feeding the record across the board, means for rewinding the record comprising two normally separated members, one of said members being operatively connected to the spool, means for rotatably supporting the other member, means controlled by the record adapted to be engaged by the rotary member, whereby
- 50 the further rotation of the member after it has engaged the last said means will cause the member to be moved into engagement with its coöperating member, and means
- 55 for throwing the feeding mechanism out of operation when the said member is shifted.
- 60 33. In a device of the class described, the combination of a tracker-board, a record holding and a record receiving spool located respectively on the opposite sides of the tracker-board, means for feeding the record

across the board, means for rewinding the record comprising two normally separated members, one of said members being operatively connected to the spool, a bodily movable support within which the other member is rotatably mounted, an inclined guide for the support and means adapted to be engaged by the rotary member, whereby a further rotation of the member after it has engaged the last said means will move the support to bring the rotatable member into contact with its operating member and throw the feeding mechanism out of operation.

34. In a device of the class described, the combination of a tracker-board, a record holding and a record receiving spool located respectively on the opposite sides of the tracker-board, means for feeding the record across the board, means for rewinding the record comprising two normally separated members, one of said members being operatively connected to the spool, a bodily movable support within which the other member is rotatably mounted, an inclined guide for the upper end and a guide for the lower end of the support, means adapted to be engaged by the rotary member, whereby a further rotation of the member after it has engaged the last said means will move the support to bring the rotatable member into contact with its operating member and throw the feeding mechanism out of operation, means for locking the support in its adjusted position, and means for releasing the support.

35. In a device of the class described, the combination of a tracker-board, a record holding and a record receiving spool located respectively on the opposite sides of the tracker-board, means for feeding the record across the board, means for rewinding the record comprising two normally separated members, one of said members being operatively connected to the spool, a bodily movable support within which the other member is rotatably mounted, an inclined guide for the upper end and a guide for the lower end of the support, means adapted to be engaged by the rotary member, whereby a further rotation of the member after it has engaged the last said means will move the support to bring the rotatable member into contact with its operating member and throw the feeding mechanism out of operation, means for locking the support in its adjusted position, means controlled by the record for releasing the support and means for returning the support to its normal position when released.

36. The combination, in apparatus of the class described, of a tracker board, a holding spool and a receiving spool, a record sheet adapted to wind from one to the other, driving mechanism common to both of said

spools, a clutch for connecting said driving mechanism to said holding spool, a shiftable shaft for connecting said driving mechanism to said receiving spool, a member common to said clutch and said shiftable shaft for actuating to simultaneously disconnect the driving mechanism from one of said spools and connect it with the other of said spools, and mechanism controlled by the record and operable when one or the other of said spools is empty for actuating the

common member to reverse the direction of movement of the record.

In testimony whereof I have signed my name to this specification, in the presence of 15 two subscribing witnesses, on this 14th day of September A. D. 1907.

EUGENE T. TURNER.
